Primary Examiner — Kevin K Rudzinski*Assistant Examiner* — Richard Kearney(74) *Attorney, Agent, or Firm* — Michael Best & Friedrich, LLP**CLAIM**

We claim the ornamental design for a light fixture, as shown and described.

DESCRIPTION

FIG. 1 is a perspective view of a light fixture showing our new design.

FIG. 2 is a bottom view of the light fixture shown in FIG. 1; and,

FIG. 3 is a cross-section view of the light fixture shown in FIG. 1 viewed along section 3-3.

The broken lines shown in the drawings illustrate portions of the light fixture that form no part of the claimed design.

1 Claim, 3 Drawing Sheets---
